CLAIM

The ornamental design for bracket for gutter mounted lighting devices, as shown and described.

DESCRIPTION

FIG. 1 is a perspective view of a bracket for gutter mounted lighting devices;

FIG. 2 is a top plan view thereof;

FIG. 3 is a bottom plan view thereof;

FIG. 4 is a side perspective thereof;

FIG. 5 is another side perspective view thereof, shown from the side opposite that shown in FIG. 4;

FIG. 6 is a bottom, front perspective view thereof;

FIG. 7 is a rear perspective view thereof;

FIG. 8 is a perspective view of the bracket for gutter mounted lighting devices, shown in an environment of use;

FIG. 9 is a top plan view thereof;

FIG. 10 is bottom plan view thereof;

FIG. 11 is a side elevation view thereof;

FIG. 12 is a side elevation view thereof, shown from the side opposite that shown in FIG. 11;

FIG. 13 is a front elevation view thereof; and,

FIG. 14 is a rear elevation view thereof.

The broken lines shown in the drawings illustrate environmental structure that forms no part of the claimed design.
